Peter Payson Design for Carpeting
Patented 10 April 1849

P
Peter Dawson Lowell Mass

Letters Patent No 214 dated April 10th 1840

The schedule referred to, in these Letters Patent, and inclosing
part of the same?

To all to whom these presents shall come: We it known that
of Peter Dawson of Lowell in the County of Middlesex and
State of Massachusetts have invented or designed a new
pattern to be woven or printed on carpeting, &c, and that
the following is a full, clear, and exact description of
the principle or character which distinguishes it from all
other things before known, reference being had to the ac-
companying drawing numbered - 760 -

This design consists of a shield of white littered (a)
in the drawing (which is numbered 760) surrounded by
scrolls and leaves commingled, a portion of the smaller
leaves being green, the others being formed of brown and
yellow, shaded with ruby, which forms the ground

Des. 214

work of this pattern; on one side of the shield there are two white flowers (b); on the other side two red flowers (c); on the white ground of the shield there is a sprig of yellow bell flowers (d); several leaflets of this foliated border also project over on to the white ground of the shield, which is further dotted with ruby; above the shield are red and blue flowers (d & e) the branches of which appear to emanate from and are connected with the borders of the shield.

What C. desires to secure by letter of patent, is this a bone described design, for weaving into carpets, and other similar fabrics, as fully set forth in the accompanying drawing.
